[57] **CLAIM**

The ornamental design for a lamp, as shown and described.

DESCRIPTION

FIG. 1 is a perspective view of a table lamp embodiment of

the invention showing my new design;

FIG. 2 is a front elevational view of the table lamp, the rear elevational view being identical;

FIG. 3 is a right side elevational view of the table lamp, the left side elevational view being identical;

FIG. 4 is a top plan view of the table lamp;

FIG. 5 is a bottom plan view of the table lamp;

FIG. 6 is a perspective view of a floor lamp embodiment of the invention showing my new design;

FIG. 7 is a front elevational view of the floor lamp, the rear elevational view being identical;

FIG. 8 is a right side elevational view of the floor lamp, the left side elevational view being identical;

FIG. 9 is a top plan view of the floor lamp;

FIG. 10 is a bottom plan view of the floor lamp;

FIG. 11 is a perspective view of another table lamp embodiment of the invention my new design;

FIG. 12 is a front elevational view of the table lamp, the rear elevational view being identical;

FIG. 13 is a right side elevational view of the table lamp, the left side elevational view being identical;

FIG. 14 is a top plan view of the table lamp;

FIG. 15 is a bottom plan view of the table lamp;

FIG. 16 is a perspective view of another floor lamp embodiment of the invention showing my new design;

FIG. 17 is a front elevational view of the floor lamp, the rear elevational view being identical;

FIG. 18 is a right side elevational view of the floor lamp, the left side elevational view being identical;

FIG. 19 is a top plan view of the floor lamp; and,

FIG. 20 is a bottom plan view of the floor lamp.

Lamp shades are shown in broken lines in FIGS. 11-20 for illustrative purposes only and form no part of the claimed design.

The light bulbs are shown in broken lines for illustrative purposes only and form no part of the claimed design.
